CALANDRIA

Henry M. Hunter, New York, N. Y., assignor to
Goslin-Birmingham Manufacturing Company,
Inc., a corporation of Alabama

Application March 28, 1938, Serial No. 198,501

7 Claims. (Cl. 257—224)

This invention relates to evaporators and vacuum pans, and more particularly to the steam chest or calandria thereof, and has for its object the provision of improved means for effecting heat transfer in the calandria.

A more particular object of my invention is to provide, in apparatus of the character designated, an improved means for removing the non-condensable gases from the steam side of the calandria tubes.

A more specific object of my invention is to provide an improved system of baffles in the calandria whereby the steam employed for heating is more effectively distributed around the calandria tubes and in which the non-condensable gases are removed in such a manner that there is a minimum of dead air, or inactive space around the tubes.

As is known in the art to which my invention relates, one of the most obstinate problems to be overcome in the design of evaporators is the removal of non-condensable gases from the steam side of the heating surfaces. These non-condensable gases, consisting of air originally dissolved in the water or drawn in through faulty seams or leaky connections, organic acids which may be dissolved in the juices being evaporated in a previous effect, particularly carbon dioxide, some ammonia, and perhaps others, are very detrimental to heat transfer. They not only reduce the temperature of steam or vapor by exerting a partial vapor pressure, but they accumulate in certain spots, pockets or stratifications, and tend to cling to the surfaces of the tubes where they can do the most harm, being driven there by the constant flow of steam in this direction. Some of these gases are corrosive in nature and tend to pit and damage the tubes and tube sheets. Their thorough and prompt removal is therefore highly important.

In accordance with my invention I have overcome the difficulty heretofore ordinarily encountered in the removal of non-condensable gases by the provision of an improved system of baffling in a calandria having tangential steam inlets. I have found, in such a calandria, that if a steam belt open freely to the tube nest be provided around the calandria, and baffles curved in the direction of steam flow be provided in the tube nest extending from the steam belt to the down take well, with off-take means located adjacent the juncture of the down-take well and each curved baffle, that all the non-condensable gases are caused to flow toward the out-

lets and are removed directly. The tube nest, being open directly to the steam belt, without any intervening plates, affords the maximum contact of steam with the tubes, with maximum velocity flow around the tubes, and unrestricted entry into the tube nest, thereby providing optimum conditions for heat transfer.

Apparatus embodying features of my invention is illustrated in the accompanying drawing forming a part of this application in which:

Fig. 1 is a view half in elevation and half in section of an evaporator having my improved calandria incorporated therein, taken along the line I—I of Fig. 2; and

Fig. 2 is a sectional view taken along the line II—II of Fig. 1.

Referring to the drawing for a better understanding of my invention, I show an evaporator having a body 10 comprising an upper vapor chamber where separation of liquid and vapor take place, and a calandria 11 at the lower end of the evaporator body. The calandria comprises a tube nest 12, the tubes of which extend through an upper tube sheet 13 and a lower tube sheet 14. A down take well 15 extends through the center of the calandria and is also joined to the upper and lower tube sheets 13 and 14. Surrounding the tube nest 12 is a steam belt 16 formed as an annular passage in the side of the shell surrounding the tube nest, there being no baffles or plates between the steam belt and the tube nest as have heretofore been provided. Diametrically opposite tangential steam inlets 17 and 18 are connected to the steam belt so as to cause the steam entering the calandria to flow around the steam belt and directly into the tube nest 12.

Connecting the steam belt 16 and the down-take 15 are a plurality of baffles 19, 21, 22 and 23 which are joined to the upper and lower tube sheets 13 and 14, and extend to the down-take well, as seen in Fig. 1, and which cooperate to form a plurality of radial inwardly extending heating zones, each decreasing in area as it approaches the down-take well 15. The baffles 19 to 23 inclusive, as shown in the drawing, are curved in the direction of steam flow to catch and direct the stream of steam, and are spaced around the steam belt 16 whereby the steam is directed into the heating zones with a minimum of interference to its flow. While the baffles 19, 21, 22 and 23 are described as curved, it will be seen that, due to the lay out of the tube nest, a true curve cannot be obtained. The term

"curved" as used herein is therefore intended as describing the general shape of said baffles.

Located adjacent the juncture of each of the baffles 19, 21, 22 and 23 and the down-take well 15, in the bottom tube sheet 14, is a condensate outlet 24. Above the condensate outlet, in the upper tube sheet 13, is an outlet 26 for air and other non-condensable gases. A perforated tube 27 extends downwardly from the outlet 26 to a point near the lower tube sheet 14 and connects to an off-take tube 28 above the tube sheet 13, which tube 28 is connected to a pipe 29 which leads outside of the evaporator as is well understood. The condensate outlets 24 are connected to drains 25, which lead outside the evaporator and may connect to a common drainage pipe 30.

It will be apparent from the foregoing that when steam is admitted to the calandria 11 through the tangential inlets 17 and 18 into the steam belt 16 it is inclined, by its own momentum, to follow the steam belt 16 around the tube nest 11. It is drawn into the tube nest by the heat transfer through the tubes and condensation, the curved baffles 19, 21, 22 and 23 guiding the flow of the steam inwardly toward the down-take well 15, bringing about a maximum of contact with the tubes in the tube nest 12, and causing a concentration of the non-condensable gases in the restricted area of the juncture of the spiral baffles with the down-take well. The non-condensable gases now pass outwardly of the evaporator through the perforated tubes 21 and the off-take tubes 28 and 29. The condensate drains through the outlets 24 and the drain pipes 25 and 30. It will be apparent that this arrangement affords ideal heat transfer conditions, a maximum removal of non-condensable gases, and a minimum of dead space caused by non-condensable gases in the tube nest.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. A calandria having a central down-take well, a tube nest, and a tangential steam inlet, means forming an annular steam belt surrounding the tube nest, a plurality of radially extending baffles curved in the direction of entering steam flow connecting the steam belt and the down-take well, and off-take means for non-condensable gases located near the juncture of the spiral baffles and the down-take well.
2. A calandria having a central down-take well joined to the upper and lower tube sheets and a tube nest surrounding the well, a plurality of tangential steam inlets to the calandria, means forming an annular steam belt surrounding the tube nest and open freely to the tube nest, a plurality of radially extending baffles curved in the direction of entering steam flow and extending from the steam belt inwardly to join the down-take well, and outlet means for non-condensable gases and condensate in the tube sheets adjacent the juncture of the baffles with the down-take well.

3. A calandria comprising upper and lower tube sheets, a central down-take well joined to the upper and lower tube sheets, a tube nest surrounding the down-take well, radially extending curved baffles connected to the upper and lower tube sheets and extending inwardly of the tube nest to the down-take well forming between them separate radial heating zones of decreasing cross sectional area, a plurality of tangential steam inlets into the calandria, means defining a steam belt to which the inlets are connected and completely surrounding the tube nest, the tube nest being freely open to the steam belt, and off-take means for non-condensable gases and condensate in the tube sheets adjacent the juncture of the baffles and the down-take well.

4. In a calandria, a tube nest, a down-take well disposed centrally of the tube nest, an outer shell surrounding the tube nest, an annular steam passage formed in the outer shell, tangential steam inlets to the steam passage, baffle walls in the tube nest curved in the direction of entering steam flow and dividing it into separate converging heating zones, said walls extending radially inward to the down-take well, and off-take means for non-condensable gases and condensate disposed adjacent the juncture of the curved walls and the down-take well.

5. A calandria comprising a shell enclosing a tube nest having a central down-take well, means in the shell forming an annular steam passage surrounding the tube nest and freely connected therewith, tangential steam inlets into the annular passage, a plurality of baffles curved in the direction of entering steam flow dividing the tube nest into a plurality of converging heating zones and guiding the steam radially inwardly of the tube nest, and means adjacent the down-take well to remove condensate and non-condensate gases.

6. A calandria comprising a shell enclosing a tube nest having a central down-take well, means in the shell forming an annular steam passage defined by the outer wall of the shell and the tube nest so as to be freely connected with the latter, tangential steam inlets into the annular passage, radially extending baffles curved in the direction of entering steam flow dividing the tube nest into a plurality of converging heating zones and guiding the steam inwardly of the tube nest, and means on the windward side of each of said baffles adjacent its juncture with the down-take well to remove condensate and non-condensable gases.

7. In a calandria, the combination with an outer shell having an annular steam passage formed therein, a tube nest enclosed by the shell and open to the steam passage and a central down-take well, of a plurality of curved baffles, each extending radially inward from the steam passage to divide the tube nest into a plurality of heating zones, said baffles leading inwardly of the tube nest to the down-take well and being curved in the direction of entering steam flow, off-take means for non-condensable gases and condensate disposed in the areas formed the junctures of the baffles and the down-take well, and tangential steam inlet means leading into the passage.

HENRY M. HUNTER. 70
